UNITED STATES PATENT OFFICE

WALTER M. KEENAN, OF NEW YORK, N. Y., ASSIGNOR, BY MESNE ASSIGNMENTS, TO
METROPOLITAN ENGINEERING COMPANY, A CORPORATION OF NEW YORK

AUTOMOBILE STORAGE

Application filed April 23, 1928. Serial No. 272,014.

This invention relates to an improved means for handling and storing automobiles in different parts of the building and aims to provide means for increasing the speed in handling. The invention will be fully apparent from the following specification when read in connection with the accompanying drawings in which—

Fig. 1 is a sectional elevation through a storage building illustrating one embodiment of the invention;

Fig. 2 is a sectional plan on line 2—2 of Fig. 1;

Fig. 3 is an elevation with parts shown in section illustrating the application of my invention to existing buildings of the apartment house, office building or department store type;

Fig. 4 is a view from the right of Fig. 3, the lower portion of the building being shown in section;

Fig. 5 is a sectional plan on line 5—5 of Fig. 4.

Referring first to Figs. 1 and 2, 20 represents an automobile storage or garage building provided with a series of floors at different elevations as indicated by numerals 1 to 15 above the normal street level 22. The building is also equipped with sub-surface storage levels indicated at 16 and 17.

In the embodiment of Fig. 1, the building is designed to accommodate automobiles in different tiers, one tier indicated generally by numeral A being located at one side of the building and another tier indicated by numeral B at the other extremity of the building. The tiers A and B are each of a length corresponding to space required to accommodate the longest car likely to be stored.

An intermediate tier C consists of rooms or storage compartments of a length adapted to store two or more cars arranged end to end or to take care of cars of extremely long wheel-base.

For quickly handling cars to be stored, I provide a multiple elevator comprising spaced flexible carriers 24 passing over suitable guide wheels 26, these carriers hav-

ing suspended therebetween a multiplicity of car-carrying cages 28. In the embodiment shown, each cage is provided with an upper platform 30 and a lower platform 32 so that a plurality of cars can be handled by each cage. The elevator is driven by any suitable prime mover such as an electric motor as indicated, for example, at 30.

In practice, cars to be stored will be driven in through the doorway 32 usually at the street level as indicated by the entering car 34 in Figs 1 and 2. This car will make a left turn as indicated by the arrow to the position shown at 36 and when either platform 30 or 32 of the cage 28 is brought in position, car 36 may be driven straight onto the elevator and carried to any unoccupied floor. For example, as shown in the drawings, a car 38 can be stored in one of the upper floors of the tier B. A car 40 carried by the same elevator cage 28 by which the car 38 was handled is shown leaving the cage. The spacing between the floors and the spacing of the elevators may be arranged so that a great number of cars can be simultaneously either loaded or discharged. As shown in Fig. 1, four of the cages of the elevator are shown in either loading or discharging position and as each of these cages is capable of holding two cars, it is clear that eight cars can be handled simultaneously. The spacing of the cages shown in the drawing is merely a diagrammatic representation and, of course, it will be appreciated that by a suitable choice of dimensions a much greater number of cars can be simultaneously handled.

The arrangement of Figs. 3 to 5 inclusive is adapted particularly for installation in existing buildings such as apartment houses or office buildings and illustrates how a great number of cars can be stored in sub-cellars or below grade. In this embodiment of the invention, the cars to be stored enter through a doorway 42 at the street level where they are loaded onto one of the cages 44 carried by the flexible carrier 46.

The carrier is guided on idler wheels 48—48, 50, 52, 54 and 56 which are so arranged that the cages can traverse either the

storage level 58 or 60. As thus arranged, it is clear that the cages have both a vertical and horizontal travel so that a multiplicity of cars can be stored side by side at either 5 level 58 or 60.

From the foregoing it is clear that I provide means for simultaneously loading or discharging a multiplicity of cars and also for handling a great number of cars. The 10 arrangement overcomes the objection found to exist in the use of the usual elevator in which it is necessary for a single cage to shuttle back and forth for each car handled. Moreover, my improved apparatus provides 15 means for moving the cars horizontally as well as vertically so as to position the cages for discharging cars at different stations at a single elevation or at different stations located at various elevations.

20 It is also apparent that my invention provides means for using relatively inexpensive or waste space in buildings for the parking or storage of automobiles in a convenient and expeditious manner. Where the installation is used in department stores, office buildings, apartment houses and the like, the users' cars are readily accessible in closely adjacent storage spaces for the customers, tenants, employees, and so forth. Thus 25 great numbers of cars can be parked or temporarily stored in a compact manner in such a way that they can be quickly brought to the street level for the user. It is clear that 30 by storing or parking cars as herein described, the blocking of street traffic by parked cars is avoided.

Various modifications may be made without departing from the invention as defined in the appended claims.

40 What I claim is:—

1. A building having a flexible member sustaining a multiplicity of carriers, means for guiding said flexible member, said building having an automobile entrance at the 45 street level and a plurality of rows of automobile storage compartments located one over the other below the street level with a space between said rows, said flexible member arranged to travel in said space and said multiplicity of carriers supported by said flexible member being adapted to lower automobiles from said street level entrance and transfer them laterally to compartments 50 below the street level.

2. A building having a flexible member sustaining a multiplicity of carriers, means for guiding said flexible member, said building having an automobile entrance at a pre- 60 determined level and a plurality of rows of automobile storage zones located one over the other below the street level with a space between said rows, said flexible member arranged to travel in said space and a multiplicity of carriers supported by the flexible 65

member adapted to transfer them laterally to said zones below the street level.

3. A building having a flexible member 70 sustaining a multiplicity of carriers, means for guiding said flexible member horizontally, said building having an automobile entrance at a predetermined level and a plurality of rows of automobile storage zones located one over the other below the street level with a space between said rows, said flexible member being arranged to travel in said space and said carriers being adapted to transfer automobiles laterally to desired zones below the street level.

4. A building having a flexible member 80 having a horizontally traveling portion below the street level, means for guiding said flexible member, said building having an automobile entrance at a predetermined level, a plurality of automobile storage zones located one over the other below the street level, said flexible member being arranged to travel lengthwise of said zones, and said carriers being adapted to lower automobiles from said entrance and transfer them laterally to said zones below the street level.

5. A building having a flexible member 90 having a horizontally traveling portion below the street level, means for guiding said flexible member, said building having an automobile entrance at a predetermined level, a plurality of automobile storage zones disposed in a substantially horizontal plane below the street level, said flexible member being arranged to travel lengthwise of said 100 zones, and said carriers being adapted to transfer automobiles from said entrance to any of said zones.

In witness whereof, I have hereunto signed my name.

WALTER M. KEENAN.
